UNITED STATES PATENT OFFICE

167,047

RELAY OR SIMILAR ARTICLE

Lewis E. Massie, Los Angeles, Calif., assignor to
James Goodman, Los Angeles, Calif.

Application July 9, 1951, Serial No. 15,792

Term of patent 14 years

(Cl. D26—13)

To all whom it may concern:

Be it known that I, Lewis E. Massie, a citizen of the United States, residing in the city of Los Angeles, in the county of Los Angeles, and State of California, have invented a new, original, and ornamental Design for a Relay or Similar Article, of which the following is a specification, reference being had to the accompanying drawing, forming a part thereof.

Figure 1 is a perspective view of a relay or similar article, showing my new design.

Figure 2 is a top plan view of the same.

Figure 3 is a side elevation view of the same.

Figure 4 is another side elevation view of the same.

I claim:

The ornamental design for a relay or similar article, as shown.

LEWIS E. MASSIE.
